FIG. III

UNITED STATES PATENT OFFICE

2,089,148

LADING AND CONDITION INDICATOR FOR
FREIGHT CARS

Ralph A. Light, Cynwyd, and Joseph W. Price, Jr.,
Philadelphia, Pa., assignors to The United
States Metallic Packing Company, Philadel-
phia, Pa., a corporation of Pennsylvania

Application January 20, 1936, Serial No. 59,870

8 Claims. (Cl. 40—70)

This invention relates to safety appliances and analogous means for indicating the character and condition of the contents of freight cars, or the like, and it has for its primary object 5 the provision of a novel form of lading and condition indicator including a rotative element characterized by differentiating colors which is movable so that any one predetermined color, or a combination of colors, can be brought into 10 registration with a sight opening and thereby depict the character and condition of the car freight.

Another object of the invention is to provide a lading and condition indicator preferably 15 adapted for use on railroad freight cars whereby they can be more expeditiously handled, while the need for application of external markings incident to inspection or the use of "tags" is eliminated, and at the same time the indicator 20 is of a type and construction to readily withstand the ravages of constant exposure, or the accidental loss of any of its parts incident to changing the character of the freight.

Other objects and advantages of the invention 25 will be either specifically referred to or become apparent from the following description, of a preferred embodiment, when considered in conjunction with the accompanying sheets of drawings; while the characteristic features of 30 said invention are more concisely expressed in the claims at the conclusion of this specification.

In the drawings:

Fig. I is a front elevation showing the improved lading and condition indicator for 35 freight cars.

Fig. II is a vertical section of the device, taken as indicated by the arrows II—II in Fig. I.

Fig. III is a view corresponding to Fig. I with 40 a portion of a plate component of the device broken out to expose important features which would otherwise be hidden.

Fig. IV shows an inspector's card adapted to be used in conjunction with the indicator; and, 45 Fig. V is a detail sectional view, taken as indicated by the arrows V—V in Fig. III showing the provisions made in the plate component of the device for reception and retainment of the inspector's card.

50 As herein illustrated, the indicator of this invention comprises a plate-like component 6, which may be cast or fashioned from sheet metal, with a rearward flange 7 extending around its top and side edges. The plate component 6 is adapted to be secured to a board 8 of corre-

sponding size by means of screws 9 with formation of an interspace 10; and said board is in turn permanently fastened to the side of a railroad car or other type of freight carrier, not shown. Substantially centrally, near the bottom, the plate component 6 is provided with a circular window or sight orifice 11, and to the right of said orifice, with a lateral pocket 12 for insertion of a two-fold inspector's ticket or card 13 such as shown in Fig. V, said pocket being open at one end to facilitate insertion of the card 13 and open at the back, as indicated at 14 in Fig. III, to provide outlet for any water that might get into such pocket.

Slightly below the center of the plate-like component 6 there is fitted to its inner side an axis pin or shouldered stud 15, conveniently secured rigidly in place by a washer 16 and lock nut 17, and said stud is provided with a head 18 affording abutment for a rotative classification 20 indicator or semaphore disc 19. This semaphore disc 19 is conveniently formed with a surrounding bead or stiffening rim 20, an inner concentric bead 21, and a series of circumferentially spaced tabs 22, 23, having slots 24 therethrough. The 25 semaphore disc 19 also has its outer face suitably divided into six (for example) equal sectoral sections 25, 26, 27, 28, 29 and 30, intermediate the rim 20 and bead 21; said sections being, respectively, colored to depict white, red, 30 black, blue, green and yellow; or any other desired arrangement of coloring may obviously be adopted to suit the classes of cars used on different railroads. It is also to be particularly noted that the slotted tabs 22 are located centrally of the outer curvatures of the several sectoral sections 25—30; while the tabs 23 overlap the radial junctures of the adjoining differently-colored segmental sections, as clearly 35 shown in Fig. III, and for a purpose hereinafter explained.

Intermediate the semaphore disc 19 and the inner face of the plate-like component 6, and frictionally coactive with said inner face and the bead 21 of said disc 19, is a somewhat sectoral auxiliary indicator 31 having a surrounding bead 32, a cut-out 33 with inwardly projecting tabs 34, 35, respectively bearing the legends "empty" and "loaded"; as well as an elongated circumferential tab 36 having two slots 37, 38 50 therethrough, for purposes later on set forth.

Referring again to the inspector's card or lateral pocket 12, it is to be observed from Figs. III and V that the same is provided with a plurality of openings 39 through the plate wall 6 to 55

reduce frictional adherence thereto of the card 13, as well as a medially-located outset or embossment 40 serviceable to hold the card 13 against the confronting portion of a face plate 5 41 that conforms with the plate-like component 6, and which is conveniently clamped thereto by the screws 9 with interposition of lock washers 42, in an obvious manner.

As best appreciated from Fig. I, and in order 10 that the meaning of the different color or colors exposed to view through the sight orifice 11 may be readily understood, the face plate 41 is provided with columnar divisions 43 corresponding 15 with the series of colors included in the segmental sections 25-30 of the classification indicator or semaphore disc 19, and other divisions 44 depicting selected combinations of colors, such as 30-25, 29-30, 28-29, and 27-26. Associated with each of the divisions 43, 44 are aligned divisions 45 including informative data as to the type 20 of car and the freight carryable therein, the attention desirable before loading, as well as the condition of the car generally. Obviously the informative data contained in the divisions is subject to change to suit the varying classes of cars 25 used by the respective railroads.

In use, it will be readily understood that when 30 the car is inspected the semaphore disc 19 can be readily turned on its pivot 15, by application 35 of the fingers to the tabs 22, until the proper color, or combined colors, that correctly indicate the condition of the car to which the device is fixed, registers with the sight opening 11, whereupon a conventional car seal 46 is engaged 40 through the slot 47 in a depending offset or tab 48 of the plate-like component 6, as well as through the slot 37 of the auxiliary indicator 31, and the selected color slot 24 (for example) of the classification indicator or semaphore disc 45 19, thus locking the parts 31, 19 in correct position, to not only depict whether the car is "loaded" or "empty" but, in addition, the character of the freight and condition of the car. Obviously, when the car is "empty" the auxiliary indicator 31 will be swung counterclockwise, from the position 50 shown in Fig. I, to move the legend "empty" into registration with the sight orifice 11, stops 49 serving to limit movement of said indicator, in an obvious manner. Furthermore it will be readily understood that when one or other of the 55 combination colors on the semaphore disc 19 is moved into registration with the sight orifice 11 that the car seal 46 will be passed through the slot 24 of the associated tab 23; also that when the car is "empty" said seal will be inserted through the slot 38 of the auxiliary indicator 31.

From the foregoing disclosure, taken in connection with the accompanying drawings, it is thought the complete construction, operation, and 60 numerous advantages of the invention will be readily appreciated by those skilled in the art; and that various minor modifications may be effected without departing from the spirit and scope of said invention as more particularly featured in the following claims.

Having thus described our invention, we claim:

1. A lading and condition indicator for freight cars and the like comprising a plate-like component flanged to define a downwardly-open

closure, a sight opening near said component lower edge, a semaphore disk rotatively mounted on said component within the enclosure portion thereof, said disk having segmental differentiating indications on its face, and means whereby the indications can be individually, or in adjoining pairs, displayed in selective registration with the sight opening. 5

2. A lading and condition-indicator for freight cars and the like according to claim 1, including 10 means whereby the semaphore disk can be secured against movement after adjustment.

3. A lading and condition indicator for freight cars and the like according to claim 1, wherein 15 the semaphore disk is provided with apertured-tabs projecting beyond its periphery, corresponding in position to the sectoral indications on its face, adapted for registry with an aperture in the plate to receive a securing means.

4. A lading and condition indicator for freight 20 cars and the like according to claim 1, wherein the semaphore disk is provided with an inner and circumferential stiffener beads, said disk also having peripherally-projecting tabs with circumferentially elongate apertures therein, corresponding 25 in position to the indications on its face, and adapted for registry with a corresponding elongate aperture through the plate-like component for passage of the metallic ribbon of a conventional car seal. 30

5. A lading and condition indicator for freight cars and the like, wherein the semaphore disk is provided with peripherally projecting tabs corresponding in position to the indications on its 35 face, said projections being of a size to extend beyond the lower edge of the plate-like component for accessibility in turning the disk; and wherein said projections are provided with elongate apertures for selective registry with an apertured offset below the plate-like component to receive means for securing the disk against movement after adjustment. 40

6. A lading and conditioning indicator for freight cars and the like in accordance with claim 1 wherein the indications consist of differently colored sectoral areas. 45

7. A lading and condition indicator for freight cars and the like according to claim 1, wherein the indications consist of differently colored sectoral areas and wherein the disk has apertured tabs projecting outwards of its periphery, some of said tabs being centrally aligned with the segmental areas and others at the radial dividing lines between said areas, and all of said apertured tabs being adapted for registry with an apertured tab below the plate-like component, to receive a suitable securing means, with the solid colors of selected areas or portions of adjoining areas exposed at the sight opening in the plate. 50

8. A lading and conditioning indicator for freight cars and the like in accordance with claim 1 including a peripherally stiffened sector coaxially mounted with the semaphore disk and carrying "empty" and "loaded" indications capable of selective display with predetermined sectoral 55 indications of said disk at the sight opening. 60
